CLAIM

I claim the ornamental design for a bag insert, as shown and described.

DESCRIPTION

FIG. 1 is a perspective view of a bag insert showing my new design;

FIG. 2 is a front elevational view of the bag insert of FIG. 1;

FIG. 3 is a rear elevational view of the bag insert of FIG. 1;

FIG. 4 is a top plan view of the bag insert of FIG. 1;

FIG. 5 is a bottom plan view of the bag insert of FIG. 1;

FIG. 6 is a right side elevated view of the bag insert of FIG. 1;

FIG. 7 is a left side elevated view of the bag insert of FIG. 1;

FIG. 8 is perspective view of a second embodiment of a bag insert;

FIG. 9 is a front elevational view of the bag insert of FIG. 8;

FIG. 10 is a rear elevational view of the bag insert of FIG. 8;

FIG. 11 is a top plan view of the bag insert of FIG. 8;

FIG. 12 is a bottom plan view of the bag insert of FIG. 8;

FIG. 13 is a right side elevated view of the bag insert of FIG. 8; and,

FIG. 14 is a left side elevated view of the bag insert of FIG. 8.

1 Claim, 14 Drawing Sheets
